UNITED STATES PATENT OFFICE.

WILLIAM BERTRAM BOLLES, OF MILWAUKEE, WISCONSIN.

ANTIPANIC-LOCK-OPERATING MECHANISM.

1,288,816.

Specification of Letters Patent. Patented Dec. 24, 1918.

Application filed December 18, 1916. Serial No. 137,499.

To all whom it may concern:

Be it known that I, WILLIAM B. BOLLES, a citizen of the United States, residing at Milwaukee, in the county of Milwaukee and 5 State of Wisconsin, have invented a certain new and useful Improvement in Antipanic-Lock-Operating Mechanism, of which the following is a full, clear, and exact description.

10 This invention relates to what is known in the trade as an anti-panic lock, which devices are placed upon doors forming closures for the exits of buildings, and are so designed and arranged that the lock operating 15 mechanism may be easily operated by the contact of any portion of the body of a person with the lock operating mechanism, thus not necessitating the turning of a knob, so that in the event a crowd surges against 20 the door closing the exit, the lock operating mechanism will be easily operated and so permit the door to swing outwardly and permit egress from the building.

The object is to provide a locking mechanism which permits the door to be kept locked, but also permits a ready operation 25 of the locking mechanism from the inside of the door.

The object of this invention is to provide 30 a lock and lock operating mechanism which is of simple construction and dependable in its operation.

Generally speaking, the invention may be 35 said to comprise the elements and combinations thereof set forth in the accompanying claims.

Reference should be had to the accompanying drawings forming a part of this specification in which Figure 1 is a partial 40 elevation of a door in its usual mounting, equipped with a lock and lock operating device of my invention; Fig. 2 shows a form 45 of mortise lock which may be used in connection with the lock operating mechanism of my invention; Fig. 3 shows partially in elevation and partially in section a door equipped with a lock and lock operating mechanism; Fig. 4 is a rear elevation of one form of lock operating mechanism; Fig. 5 50 shows an elevation of a door equipped with a different form of locking mechanism and in connection therewith a lock operating mechanism of my invention; Fig. 6 is a side elevation with portions in section of a modified form of lock operating mechanism; Fig. 7 is a rear elevation of the showing in

Fig. 6; and Fig. 8 is a transverse section showing an operating lever and connecting parts for the lock operating mechanism.

The lock as here shown may be provided 60 with a key opening which will coöperate with a key-hole which opens to the exterior of the door, so that the lock may be operated by a key inserted upon the exterior of the door. Other types of locks may be used, 65 but the main object here sought is to provide accessible and easily operable mechanism which will under all conditions operate the lock of the door.

In Fig. 1 a door is indicated at 1, which 70 is hinged and mounted between the usual door jambs 2, at the usual place in the door, and in the edge of the door there is mortised in, a lock such as indicated in Fig. 2. This lock is of a well-known type which 75 may be purchased upon the open market, and no particular description of the lock will be given except to indicate the portion of the lock which coöperates with the lock operating mechanism of my invention; and 80 at this point I wish to state that in making reference to this particular lock I do not confine myself to a lock having the particular operating mechanism herein shown and described, as other locks may be used which 85 will coöperate with the lock operating mechanism in the manner herein described.

Referring to Fig. 2, the locking bolt or latch is indicated at 3. This latch has a rearwardly extending portion 4 which has a 90 head 5. The head is engaged by a reciprocating member 6 which has a hooked head 7 that engages with the head 5. At the rear portion the member 6 engages with an arm 8 of a pivoted lever, this lever being pivoted at 95 9. The lever also has an arm 10 which co-operates with an operating member 11. The operation of so much of the lock as shown and described, will be readily understood, for when the lever 11 is pressed upwardly, 100 the arms 10 and 8 are moved in a direction which results in pulling the latch or bolt 3 inwardly with respect to the lock casing. The various elements in the lock are so arranged that by spring pressure they will 105 be returned to their normal position when pressure against the member 11 is relieved.

Upon the inside of the door there is secured a casing 12. This casing at the lower portion is provided with a recessed 110 part 13 that receives the lower end of a movable member 14. At the upper part of

the casing there is a recessed member 15 which receives a spring 16. This spring bears upon the upper end of the member 14 and the normal action of the spring is to 5 depress or push the member 14. The back portion of the casing is closed by a plate member which is engaged at 17 in Fig. 3, the plate member coöperating with the member 14 to hold the same within the casing.

10 Upon the outside of the casing 12 there is pivoted an arm 18. This arm extends outwardly and is in position to be engaged by the person desiring to operate the locking mechanism on the door. The arm is pivoted 15 as indicated at 19, and has a portion 20 which extends behind the pivot 19. This portion 20 extends within a recess 21, formed in the member 14. The member 20 has a rounding surface which engages with the 20 opening 21 and is designed so as to have an easy fit within the recess 21. Also the width of the recess 21 is but little greater than the width of the portion 20. As the lever 18 is moved inwardly toward the door to the position 25 indicated in dotted lines in Fig. 3, the head or end 20 coöperates with the member 14 causing the same to be raised against the action of the spring 16, and when pressure against the lever 18 is removed, the action 30 of the spring 16 is to return the member 14 to its original position.

It will be noted that the head 20 while moving the member 14, assists materially in guiding this member and keeping it in 35 alinement.

In the door itself there is formed a recess 23, and this recess is adjacent the lower part of the lock and more particularly that portion of the lock which accommodates the 40 presser member 11. Into the recess 23 there extends a pin or arm 24, this arm being secured to the member 14 and moving with it. The arm 24 is positioned to be directly below the presser member 11 of the lock so that 45 when the member 14 is raised by operation of the arm 18, the pin 24 will contact with the presser member 11 for the purpose of withdrawing the latch or bolt 3 in a manner which will be understood from the preceding 50 description.

The member 24 is positioned with respect to the member 11 of the lock so that the movement of the arm 18 will move the pin 24 the proper distance to operate the presser 55 member 11 of the lock, that is to say, if the movement of the arm 18 is of such an amount that the pin 24 would move a greater distance than the presser member 11 of the lock, the pin 24 will be spaced from the 60 member 11 of the lock so that the total movement of the member 24 will be no greater than is necessary to operate the member 11 of the lock.

In Fig. 5 there is represented a door 25 65 which is equipped with a different type of

locking mechanism than heretofore described. The locking mechanism in the figure to which reference has been made comprises a bolt 26 at the top of the door, and a bolt 27 at the lower portion of the door, these bolts being suitably held to 70 permit reciprocation. The bolts 26 and 27 are adapted to engage suitable openings formed in the lower sill of the door and the upper portion of the door case. The 75 bolts 26 and 27 are operated by suitable rods 26^a and 27^a, which preferably, although not necessarily, are made integral with the bolts.

Upon the face of the door is a casing 28. This casing is secured to the door in any 80 desired manner. Within the casing there is a reciprocating member 29 and a reciprocating member 30. These members are in alinement and are suitably held within the casing to permit their reciprocation. The rear portion of the casing is closed by a cover 31 which holds the parts within the casing and assists in guiding them in their reciprocating movement.

The lower portion of the member 30 is 90 provided with a recess 32 which accommodates a portion of the spring 33, the other end of the spring engaging with an end of the member 29. The spring 33 normally acts to push the members 29 and 30 apart. 95

Pivoted to the casing 28 is a lever 34. This lever is mounted upon a pin 35 which is screw-threaded into a suitable opening in the casing. The pivoted portion of the lever 34 is in front of the member 29, and for this purpose the member 29 is mortised out to form an opening as indicated at 36 in Fig. 6. This permits the lever 34 to swing about its pivot, at the same time permitting longitudinal movement of the member 29. 100

The lever 34 is pivoted as heretofore described, at the central portion thereof, and at the ends is pivotally secured to members 37 and 38 which are respectively pivoted to arms 39 and 40, which are respectively carried by the members 29 and 30. It will thus be seen that the members 29 and 30 are joined to each other in such a fashion that movement imparted to one will effect a movement of the other and in a direction 110 opposite to that in which the first member is moved; that is to say, if the member 29 be elevated, the member 37 will be raised, causing the member 34 to be moved to a substantially horizontal position which will in turn, through the member 38, cause the member 30 to be moved inward or toward the member 29, and against the action of the spring 32. When the force moving the member 29 as 120 just described, is removed, the expansion of the spring 32 will push the members 29 and 30 apart and the connecting link mechanism just described will be caused to assume the 125 position shown in full lines in Fig. 7.

The member 30 is connected with the rod 130

26^a which operates the upper bolt 26, while the member 29 is connected with the rod 27^a which operates the bolt 27.

In the casing there is mounted an arm 44. 5 This arm is pivoted to the casing as indicated at 41. Behind the pivot 41 there is an extending portion 42, the surface of which is in part cylindrical. This portion 42 extends into a slot 43 formed in the member 29, and as previously described with respect to the construction shown in Figs. 1 to 4, the member 42 has a working fit in the slot 43 so that when the lever 44 is moved, and as a consequence, motion is imparted to 10 the member 29, the head 42 in addition to moving the member 29 serves to guide the member 29 in its movement.

From what has previously been described, the operation of the device will be apparent.

20 Having thus described my invention, what I claim is:

1. In combination with a door and locking bolts therefor, a casing adapted to be secured upon the door, two members mounted 25 within the casing and guided in their movement by the casing said members being adapted to reciprocate in opposite directions parallel with the door, means connecting the said members with the locking bolts, 30 a lever pivoted between its ends upon the casing, links connecting the ends of the lever with the said two members whereby the said two members operate in unison, means within the casing for normally urging the two members away from each other, an operating member pivoted upon the outside of the door, a direct articulated connection between the operating member and one of the first mentioned members.

40 2. In combination with a door and locking bolts therefor, a casing adapted to be se-

cured upon the door, two members mounted upon the door in substantial alinement, said members being adapted to reciprocate in opposite directions and parallel with the door, 45 means connecting the said members with the locking bolts, a spring engaging the adjacent ends of the said members and normally urging them apart, a lever pivoted between its ends, upon the casing, links connecting the 50 ends of the lever with the said two members whereby the two members operate simultaneously, an operating member pivoted upon the outside of the door, a direct articulated connection between the operating member 55 and one of the first mentioned members.

3. In combination with a door, and locking bolts therefor, a casing adapted to be secured upon the door, two members mounted 60 upon the door and adapted to reciprocate in opposite directions parallel with the door, connections between the said members and the locking bolts, means normally urging the two members away from each other, one of the said members having a cut out portion, a lever pivoted between its ends to the casing 65 and in part occupying the cut out portion of one of the first mentioned members, links connecting the opposite ends of said lever with the said members whereby the members operate together, an operating member pivoted upon the outside of the door, a direct articulated connection between the operating members and one of the first mentioned 70 members.

In testimony whereof, I hereunto affix my signature in the presence of two witnesses.

WILLIAM BERTRAM BOLLES.
